UNITED STATES PATENT OFFICE

LEWIS G. YOUNG, OF BRONXVILLE, NEW YORK

AEROFOIL CONSTRUCTION

Application filed June 21, 1929. Serial No. 372,651.

This invention relates to the construction of aerofoils or aeroplane wings and is particularly concerned with the provision of a spar for internally bracing a wing which is curved along its span.

In my copending application, Serial No. 372,650 filed June 21, 1929, there is described a wing spar which is curved along its span. The present invention is concerned with a 10 modification of the spar described in said application. It is there proposed to construct a wing which is laterally curved and which has a lifting surface relatively near the fuselage of the aeroplane, and which has 15 a stabilizing surface extending laterally beyond the lifting surface and making a dihedral angle therewith. The present spar is especially adapted for internally bracing such a wing. This spar in addition to being 20 light in weight, simple to manufacture, and having a high factor of safety, is internal of the wing and takes such form that the wing surfaces coincide with the upper and lower faces of the spar, the wing curves 25 being determined by the spar.

The main feature of the invention thus resides in the provision of a spar for internally bracing a wing which has a dihedral angle intermediate its ends whereby the lateral stability of the plane is tremendously increased and, at the same time, a high factor of safety is maintained in the construction.

Other objects and advantages will be apparent from the following detailed description of a preferred embodiment of my invention in connection with the accompanying drawings, wherein:

Figure 1 is a plan view of a wing constructed according to the present invention.

Figure 2 is a front elevation of the wing.

Figure 3 is a front view of the forward spar shown in Figure 1.

Figures 4 to 10 inclusive, are cross sections of the wing taken on the lines 4-4 to 10-10 inclusive, in Figure 1, and looking in the direction of the arrows.

Figure 11 is a front view of a single wing spar extending on both sides of the fuselage.

Figure 12 is a cross section of the wing

taken on the line 4-4 of Figure 1, and showing a modified form of construction.

It will be understood that throughout the description the term "longitudinal" refers to a dimension fore and aft of the aeroplane, 55 while "lateral" means widthwise or along the wing span thereof.

In the embodiment of the invention illustrated each wing has a supporting surface adjacent to the fuselage and near the leading edge of the wing, with a stabilizing surface longitudinally to the rear of the supporting surface and a stabilizing surface laterally beyond the lifting surface. The supporting surfaces are so curved and proportioned that the pressure resultants of the two surfaces, whether the aeroplane be inclined in one direction or the other, tend to preserve the stability of the plane. When the plane is banked, the resultant upward 70 pressure against the lower wing is increased while that against the upper wing is decreased and the plane is thus returned to a position of equilibrium. It has been found that it is desirable to construct the lifting 75 surface with a definite ratio of length (lateral dimension) to chord, namely, two to one, although other ratios, such as three to one are also possible. With a ratio of length to chord of two to one, the distances 80 of the center of pressure of the laterally stabilizing surface and of the center of upward pressure on the underside of the wing from the longitudinal axis should also be in the ratio of two to one and the distances of 85 the center of pressure of the longitudinally stabilizing surface and of the center of upward pressure on the supporting surface from the lateral axis should likewise be in the ratio of two to one.

In cross section, the present wing has a forward portion which is concave below and a rearward portion with a reversely curved longitudinally extending stabilizing surface which meets the lower forward surface. 95 Laterally, the wing is also curved and has a stabilizing surface remote from the fuselage, the center of pressure of this surface being at about twice the distance from the longitudinal axis of the plane as is the center 100

of the lifting surface. It will be understood that the two wings are symmetrical with respect to the longitudinal axis of the plane and a description of one will suffice for the other.

There is shown at *w* a wing constructed in accordance with the present invention. This wing consists, generally, of a lifting portion, being the part between the lines 4—4 and 8—8 of Figure 1, and a stabilizing portion being the part shown between 8—8 and the wing tip. This wing is connected to the fuselage of the plane 4—4, and is provided with supporting spars *a* and *a'* and with ribs *b*. The leading edge of the wing is at *c* and the trailing edge at *d*, the usual supporting members *c'* and *d'* being provided adjacent the leading and trailing edges. The wing is shown as tapering, generally, to a point *e* at the wing tip. In the cross sectional views in Figures 4 to 10 inclusive, there is shown a wing tapering in thickness and having a particular surface as will be described in detail below.

As the particular curvature of the wing along its span is of the utmost importance, the exact positions of the wings with reference to a given plane determined by the lines *s—s* in Figure 3 and *s'—s'* in Figures 4 to 10 is shown in great detail. It will be seen that the wing makes between its ends what may be termed a dihedral angle. That is, looking at the front elevation of the wing, there is at first an upward curve. The wing then curves downwardly to form a depressed portion between its ends and then curves up slightly, preferably not reaching, however, a height as great as the first raised portion assumes. This is shown best in Figures 4 to 10, wherein the reference lines *s'—s'* are horizontal and in a plane passing through the lower front corner of the spar *a*.

Since it is the particular construction of the spar which constitutes the main feature of the present invention, the spar *a* is shown in detail in Figure 3. The spar *a'* is similar in construction to the spar *a* and takes positions relative to the latter as shown in Figures 4 to 10.

The upper and lower wing surfaces are, of course, designed with generally stream line form, but the lower surfaces have more particularly a concave portion *m* and a convex portion *n*, the former being forward of the point *k* at which the curve reverses, and the latter being to the rear of said point. It will be noted that the curve *m* is approximately twice the length of the curve *n*, though this proportion is not absolutely essential. However, when these curves are in a given ratio at one wing section, the ratio should be preserved at the other wing sections. For convenience in description of the definite relationship between the lifting portion of the wing and the stabilizing portion,

it may be noted that the lifting portion between lines 4—4 and 8—8 is of trapezoidal shape with long sides of approximately twice the length of its short sides. This approximate ratio of two to one between the length and the width of the lifting section is the ratio which determines the locations of the centers of pressure, whereby the plane is properly balanced. It will be understood, of course, that this definite relationship is approximate only and is not absolute. The other portion of the wing, from the line 8—8 to the wing tip comprises the stabilizing portion of the wing and has a leading edge which sweeps back to the wing tip which is approximately in line laterally with the trailing edge of the wing at the fuselage.

In the copending case referred to above the wing spars are shown straight laterally. In the present invention the spars in addition to being curved to form dihedral angles between their ends are also curved to extend so they lie further forward longitudinally at some points along their spans than they do at others. The particular shapes illustrated in Figure 1 need not be maintained, but in general the spars should be shaped to impart to the wing maximum strength, the leading spar coinciding approximately with the centers of pressure along most of its length.

Although the wing is shown as tapering in thickness from the fuselage to the wing tip, a wing of constant thickness is also within the scope of this invention. It will also be apparent that the wings may form a dihedral angle between them, or lie generally in the same plane, and may have sweep back or make any desired angle with the line of flight. Steel I-beam spars are shown in Figures 4 to 10 inclusive, but other metal sections or wood could be used instead. The particular type of rib used forms no part of the present invention.

In Figure 11, there is shown a single spar extending on both sides of the fuselage *f* and having sections *a²* connecting the two sections *a*, each of which latter is constructed according to the present invention.

In operation, it will be appreciated that should the plane start to nose over, the rear part of the wing, as shown in Figures 4 to 10 inclusive, will tend to rise relative to the forward portion and the smooth curve of the upper surface which meets the reverse curve of the lower surface, tends to produce a drag on the movement of the wing and to return the plane to normal flying position. This is true because the rear part or trailing edge of the wing may be said to curve upwards in a reverse direction to the downward curve of the leading portion of the wing. Thus as soon as the plane starts to dive, the action of the air pressure on the

trailing edge tends to exert a force thereon which not only prevents the plane from taking an increased diving angle but actually restores the wings to a normal angle of attack.

5 Similarly, should the plane due to external forces acting thereon, tend to bank the resultant pressures on opposite sides of the fuselage will tend to right the plane because of the effect of the relative pressures on the sustaining or lifting surfaces, together with the oppositely inclined stabilizing surfaces. The equilibrium of the plane thus tends to be automatically restored 10 whenever outside forces unbalance the stability of the plane.

15 The plane may be positively controlled by ailerons, rudder and elevators, not shown. Other details of the construction of the 20 plane are not shown as they do not form any part of the present invention.

25 Further, applicant does not wish to be limited to the specific embodiment shown, save as defined in the appended claims.

20 I claim as my invention:

30 1. In a wing, a spar which is curved toward and away from the leading edge and which is formed with a dihedral angle between its ends and approximately midway 35 of the wing span and in the plane of the wing.

2. In an aeroplane having a wing formed with a dihedral angle between its ends, a plurality of spars formed in the wing and having dihedral angles between the ends thereof, the angle of the forward spar being more acute than that of the after spar.

35 This specification signed this 5th day of June A. D. 1929.
